ALBERT A. FROELICH, OF TOLEDO, OHIO.

LINOTYPE ATTACHMENT.

1,154,302.

Specification of Letters Patent. Patented Sept. 21, 1915.

Application filed October 23, 1914. Serial No. 868,314.

To all whom it may concern:

Be it known that I, ALBERT A. FROELICH, a citizen of the United States, and a resident of Toledo, in the county of Lucas and State 5 of Ohio, have invented a certain new and useful Linotype Attachment; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to linotype machines, and particularly to the assembling mechanism thereof.

The object of my invention is the provision, in combination with the assembler 20 chute spring in machines of this character, of simple and efficient means for coöperating with said chute spring to guide the type matrices to the receiver or assembling elevator, and for effecting a straightening of 25 the matrices in the assembling chute prior to their discharge into the receiver, thereby preventing the piling up of matrices at the entrance to the receiver, which has heretofore frequently occurred.

30 A further object of my invention is the provision of means for deflecting the space bands from striking the customary star wheel in their descent to the receiver or elevator, thus preventing a jumping of the 35 space bands from the receiver.

Further objects and advantages of my invention will be apparent from the following detailed description thereof.

The invention is fully described in the following specification, and while, in its broader aspect, it is capable of embodiment in numerous forms, a preferred embodiment thereof is illustrated in the accompanying drawings, in which,—

45 Figure 1 is a front elevation of the assembling mechanism of a linotype machine. Fig. 2 is an enlarged perspective view of an assembler chute spring provided with my invention. Fig. 3 is a front elevation there- 50 of with the upper portion broken away, and Fig. 4 is an elevation of a matrix of the

type commonly used in machines of this character.

Referring to the drawings, 1 designates the matrix chute of the assembling mechanism, 2 the assembling elevator to which said chute leads, which elevator for convenience will hereinafter be termed the receiver, 3 the customary assembler chute spring which extends down into the matrix 55 chute 1 adjacent to the delivery end thereof, and 4 the chute through which the space bands 5 are delivered to the receiver 2. The lower end of the assembler chute spring 3 terminates a short distance above the bottom 60 of the matrix chute 1 and is shown as being flared forward and provided at the opposite edges of its lower end with forwardly projecting spurs 6. Nothing novel is claimed 65 for this assembler chute spring, as it is the form commonly employed in machines of 70 this character.

The feature of my invention consists in attaching a guide tongue 7 in pendant manner to the front side of the assembler chute 75 spring 3, said tongue being preferably hinged to said spring, as at 8, and having its free end centrally located relative to the side edges of the lower end portion of the spring and extending a short distance below the spring, as indicated. A spring member 9 is attached to the assembler chute 80 spring 3 and yieldingly bears against the guide tongue 7 adjacent to its inner end to serve to yieldingly retain the lower end of 85 the tongue in contact with the lower edge portion of the chute spring. The lower end of the guide tongue 7 is made substantially V-form and has the point portion thereof preferably broadened lengthwise of 90 the matrix chute 1. When a matrix 10 passes down the matrix chute 1 the lower pointed end of the guide tongue 7 passes through the V-notch 11 in the upper end of the matrix, which notch is common to the 95 matrices used in this type of machine, and should the matrix be in other than true position with respect to the chute 1, the tongue 7 will coat with one wall or the other of the V-notch 11 and tend to straighten up 100 the matrix or true it with respect to the chute. The lower end of the guide tongue 7

stands in the path of movement of matrices down the matrix chute 1, but is sufficiently yieldable relative to the chute spring 3 as not to perceptibly interrupt the movement of the matrices. As the matrices pass down the chute 1 they have a wiping action against the free end of the guide tongue and are thereby prevented from being delivered to the receiver 2 in other than true 10 position.

It is preferable to have the lower end of the guide tongue 7 project below the delivery end of the space band chute 4 so that a space band dropping from the chute 4 will strike the lower end portion of the tongue 7 and be deflected outwardly thereby by a sufficient extent to clear the star wheel (not shown), which is employed in machines of this character at the entrance to 15 the receiver 2, said star wheel serving to intermittently force along the line of matrices of the receiver as each matrix or space band is delivered to the receiver. It is found in practice that without some 20 means of this character for deflecting the space bands in their descent to the receiver 2 that they frequently jump out of the receiver due to striking the star wheel. While the guide tongue 7 appears in Fig. 1 as having its outward movements limited by reason of contact with the lower end of the space band chute 4, such chute in reality has its rear side wall provided with a slot or incut (not shown) in register with the 25 tongue 7 so that the tongue is permitted to have yielding forward swinging movements relative to the assembler chute spring 3.

It is evident that the provision of the guide tongue 7 in association with the assembler chute 23 performs a dual function, namely, of straightening the matrices should they run untrue down the matrix chute 1, and of deflecting the space bands from contact with the star wheel of the 40 assembler mechanism when the space bands are delivered to the receiver 2, both of which features are important to the rapid operation of machines of this character, as the stopping of the machine to clean out the delivery end of the chute, should the same become stopped up or to replace space bands or matrices which may have jumped from the receiving end of the receiver, is therefore very largely minimized.

I wish it understood that my invention is not limited to any specific construction, arrangement or form of the parts, as it is capable of numerous modifications without departing from the spirit of the invention.

Having thus described my invention, what I claim as new, and desire to secure by Letters Patent, is,—

1. In an assembler mechanism of the class described, a matrix guiding assembler chute

spring, and a matrix triung tongue carried 65 by said spring for yielding movements relative thereto and being more easily moved from normal position than the chute spring and without disturbing the normal position of the spring.

2. In an assembler mechanism of the class described, a matrix guiding assembler chute spring, a matrix triung tongue pivotally suspended from said chute spring at a point 70 above its lower end for forward swinging movements relative thereto, and spring means for resisting a forward swinging of said tongue relative to the chute spring, said tongue being more freely moved from normal position than the chute spring.

3. The combination with the assembler chute spring in a mechanism of the class described, of a separate piece matrix guiding tongue yieldingly projecting from said spring into the path of movement of the 85 matrices to the receiver portion of said mechanism.

4. In an assembler mechanism of the class described, an assembler chute spring, and a guide tongue pivotally depending from the 90 front side of said spring and extending below its lower end.

5. In an assembler mechanism of the class described, an assembler chute spring having transversely spaced forwardly projecting 95 guide spurs at its lower end, and a guide tongue yieldingly depending from the front side of said spring and having its lower end extending down between said spurs and below the lower end of the spring.

6. In an assembler mechanism of the class described, an assembler chute spring, a guide tongue pivotally suspended from the front side of said spring with its free end projected below the spring, and spring means resist- 105 ing a forward swinging of said tongue.

7. In an assembler mechanism of the class described, an assembler chute spring, a space band delivery chute, and a guide tongue yieldingly projecting below both said spring 110 and chute to serve as a matrix straightener and as a deflecting means for space bands discharged from said chute.

8. In an assembler mechanism of the class described, an assembler chute spring, a space 115 band chute, and a guide tongue yieldingly movable relative to said spring and chute and projecting downward between the same, said tongue projecting below said chute in the path of discharge of space bands therefrom to serve as a deflecting means for such bands and having its lower end terminating below the lower end of the chute spring to serve as a straightening means for matrices in their passage to the receiver portion of 120 said mechanism.

9. In an assembler mechanism of the class described, an assembler chute spring, and a

matrix truing tongue projecting from said spring below the same and being freely yieldable relative to the spring whereby the tongue may be moved by contact of a matrix therewith without materially disturbing the normal position of the spring.

In testimony whereof I have hereunto

signed my name to this specification in the presence of two subscribing witnesses.

ALBERT A. FROEHLICH.
